(57) **CLAIM**

The ornamental design for a spout for fuel, as shown and described.

DESCRIPTION

FIG. 1 is a right side view of a spout for fuel, showing my new design in a state of use;

FIG. 2 is a right side view thereof;

FIG. 3 is a left side view thereof;

FIG. 4 is a front view thereof;

FIG. 5 is a rear view thereof;

FIG. 6 is a top plan view thereof; and,

FIG. 7 is a bottom view thereof.

The broken line showing of a nozzle in FIG. 1 is included for the purpose of illustrating environment of the article and forms no part of the claimed design.

1 Claim, 2 Drawing Sheets

FIG. 1

FIG. 2

FIG. 3

FIG. 4

FIG. 5

FIG. 6

FIG. 7
